REFRIGERATING APPARATUS

Chester S. Trigg, Dayton, Ohio, assignor to General Motors Corporation, Dayton, Ohio, a corporation of Delaware

Application July 21, 1941, Serial No. 403,327

9 Claims. (CL 62—172)

This invention relates to refrigeration and particularly to freezing water in household refrigerators.

I am aware of the fact that ice trays having a grid therein for dividing the interior thereof into ice block compartments have been provided in household refrigerator cabinets for freezing water into a plurality of ice blocks. The provision of grids in trays increases the manufacturing cost of a refrigerator and also necessitates the exertion of considerable force on the part of the user to release a grid from a tray and to break ice blocks from the grid. Recently these grids have been made with movable walls which when moved relative to one another to release ice blocks therefrom cause considerable chipping and breaking of the ice blocks. I, therefore, contemplate the provision in a household refrigerator cabinet of means for freezing ice blocks therein and for readily harvesting the ice blocks therefrom without the use of grids disposed in trays.

An object of my invention is to provide an improved method of and device for freezing water in a household refrigerator cabinet into ice blocks.

Another object of my invention is to provide means whereby water may be frozen into ice blocks within a household refrigerator cabinet without employing grids disposed in trays.

A further object of my invention is to provide means within a sharp freezing compartment of a household refrigerator cabinet for dripping water from a receptacle at spaced apart points upon a cold tray to cause freezing of the water and the building up thereof on the tray in the form of a plurality of ice blocks.

In carrying out the foregoing objects, it is a still further and more specific object of my invention to provide a water receptacle within a sharp freezing compartment of a household refrigerator which receptacle has a plurality of groups of small perforations in its bottom wall permitting water therein to drip therefrom at a substantially predetermined rate upon a cold surface of a removable tray spaced below the receptacle whereby the water is precooled in its fall from the receptacle to the tray and freezes and builds up on the tray in the form of a plurality of separated ice blocks.

Further objects and advantages of the present invention will be apparent from the following description, reference being had to the accompanying drawings, wherein a preferred form of the present invention is clearly shown.

In the drawings:

Fig. 1 is a front view of a household refrigerator cabinet having my invention incorporated therein;

Fig. 2 is a vertical sectional view of the refrigerator cabinet taken on the line 2—2 of Fig. 1 showing ice blocks being formed on a tray within a freezing compartment;

Fig. 3 is an enlarged front view of the freezing compartment within the refrigerator cabinet showing completely formed ice blocks on a tray therein;

Fig. 4 is a fragmentary top view of the water receptacle shown in Figs. 2 and 3;

Fig. 5 is a fragmentary top view taken on the line 5—5 of Fig. 3 showing the contour of the completely formed ice blocks; and

Fig. 6 is an enlarged sectional view taken on the line 6—6 of Fig. 4 showing perforated depressions in the bottom of the water receptacle.

Referring to the drawings, for illustrating my invention, I show in Fig. 1 thereof a household refrigerating apparatus comprising a cabinet 10 having outer metal panels or walls 11 and an inner metallic liner member 12 forming walls of a food storage chamber 14 within the cabinet. Liner 12 is spaced from the cabinet outer walls 11 and this space is filled with any suitable or desirable insulating material 16 (see Fig. 2). The front metal wall 11 of cabinet 10 is provided with an opening which registers with an opening in the liner 12 to provide an access opening to the food storage chamber 14. An insulated door structure 17 normally closes the access opening of chamber 14. Walls 11 of cabinet 10 extend downwardly beyond the bottom of liner 12 to form a machine compartment in the lower portion of the cabinet. The machine compartment may have a front opening normally closed by a door 18 and this machine compartment is adapted to house a refrigerant liquefying and circulating unit of a closed refrigerating system, associated with cabinet 10. The refrigerant liquefying and circulating unit (not shown) is connected with an evaporator 21 mounted in the food compartment 14 and the refrigerating effect produced by evaporator 21 chills the interior of compartment 14 as is conventional in the art. Evaporator 21 is preferably of the sheet metal type and its double metal walls are formed into a U-shape to provide a bottom wall 22 and upright side walls 23 of a sharp freezing compartment 24 within the food chamber 14. The evaporator 21 is supported by mounting clips or the like 26 closely adjacent the top portion of liner 12 so that this portion of the liner cooperates with the evaporator

side walls to form the top wall of the freezing compartment 24. A metal plate 27 is secured to the back of evaporator 21 and a door 28 is pivotally mounted on the front of evaporator 21 to complete the enclosure of the sharp freezing compartment 24 (see Fig. 2). Refrigerant evaporated in the passageways provided between the double walls of evaporator 21 cools the food storage chamber 14 and the refrigerating effect of the evaporator maintains the interior of the freezing compartment enclosure 24 below water freezing temperatures.

I mount a non-metallic pan or receptacle 31 within compartment 24 a substantial distance above the bottom wall 22 of evaporator 21 and upon supports 32 secured to the evaporator side walls. A flat metal tray member 33 is removably positioned within the compartment 24 and supported upon the evaporator bottom wall 22. The intimate thermal contact of tray member 33 with a wall of evaporator 21 causes cooling of the tray 33 to a temperature below 32° F. or to a temperature substantially corresponding to the low temperature of the evaporator walls. The bottom wall 34 of receptacle 31 is provided with a plurality of depressions or downwardly extending portions 36 which are perforated as at 37 to provide small holes in the receptacle bottom (see Figs. 4 and 6). In practicing my invention, I have found that the depressions or portions 36 prevent water dripping from receptacle 31, in a manner and for the purpose to be presently described, from flowing horizontally along the bottom of the receptacle. Therefore, the depressions or portions 36 immediately adjacent the holes of perforations 37 provide definite paths of water drippage from the receptacle 31. The formation of these definite paths of water drippage is advantageous in that the perforated depressions may be arranged in spaced apart groups of five each (see Fig. 4) over the area of the bottom surface of receptacle 31 so as to render the device capable of forming separated ice blocks on tray 33. Also in practicing my invention, I have found that the perforations or holes 37 in the bottom wall of receptacle 31 should be of a diameter of from $\frac{1}{64}$ " to $\frac{1}{32}$ " in order to restrict drippage from the receptacle in accordance with the normal temperature maintained by an evaporator within a household refrigerator cabinet and in accordance with a certain rate of drippage desired over a predetermined required period of time to cause emptying of the receptacle 31.

Having described the structural elements and the relation thereof to one another of the device disclosed to carry out my invention, I will now proceed to describe the function thereof. In order to freeze water into blocks of ice with the device disclosed and without the use of complicated expensive grid structures, the receptacle 31 may be filled with water at the sink and placed into the freezing compartment 24 or the receptacle 31 may be supported within compartment 24 and filled with water from a pitcher or other suitable vessel. The tray member 33 is of course positioned within the freezing compartment 24 below receptacle 31 and has preferably already been reduced to a temperature below 32° F. The water received in the non-metallic receptacle 31 flows through the perforation or holes 37 in the bottom wall thereof and drips onto the tray 33 where it freezes due to the tray being at substantially the same temperature as the bottom wall of evaporator 21. Water placed in receptacle 31 is relatively warm compared to the temperature of evaporator 21 and/or

compartment 24 and rapid conduction of heat from the water to walls of the evaporator is prevented by making the receptacle 31 of non-metallic material, as hereinabove stated, to thereby insure that all the water will drip from the receptacle before the temperature of water therein can be lowered to a point to cause freezing thereof. Water dripping from the receptacle 31 is chilled during its fall through the cold air within the sharp freezing compartment 24 toward tray member 33 and this precooling of the water hastens freezing when the drops of water strike the cold surface of tray 33. Due to the grouping of the perforations or holes 37 in the bottom wall of receptacle 31 in spaced apart groups of five each, there is provided definite paths of drippage of the water and when the water strikes tray 33 it begins to build upwardly in five separate frozen masses. These five frozen masses soon overlap one another and are moulded or frozen together by the time the water level has fallen substantially half way in receptacle 31 to thereby start the formation of blocks of ice as shown in Fig. 2 of the drawings. Further drippage of water upon the ice blocks being formed on tray 33 causes the water to freeze thereon and continue the building up of separate ice blocks. Due to the low temperature of air within the freezing compartment 24 and the precooling of water to a point closely approximating a freezing temperature as it drops through this cold air, the precooled water will freeze when it strikes the ice blocks on tray 33. This precooling feature along with proper spacing of the groups of depressions 36 and openings 37 therein, as disclosed, insures that further drippage of water from receptacle 31 will freeze upon the ice blocks before the water can flow onto tray 33 and mold the ice blocks to one another. The ice blocks attain a predetermined height and a somewhat irregular form when the water in receptacle 31 is emptied as shown in Figs. 3 and 5 of the drawings. To harvest the ice blocks from the sharp freezing compartment 24, tray 33 is removed from evaporator 21 and twisted to thereby break the bond between the ice blocks and the tray and permit the loosened ice blocks to be removed from the tray.

From the foregoing, it will be apparent that I have provided an improved method of, and a device for, freezing water into ice blocks. My device eliminates the necessity of employing expensive grid structures in trays for the formation of ice blocks, while at the same time produces ice blocks that are sufficiently uniform and preferably of such size as to permit their insertion into tall glasses. In my improved device the ice blocks can be readily removed with a minimum amount of effort on the part of the user of the refrigerator and without chipping or cracking the ice blocks.

While the form of embodiment of the invention as herein disclosed, constitutes a preferred form, it is to be understood that other forms might be adopted, all coming within the scope of the claims which follow.

What is claimed is as follows:

1. A refrigerating apparatus comprising in combination, a cabinet provided with a food storage chamber having an evaporator of a refrigerating system therein, said evaporator being formed to provide walls of a freezing compartment within said chamber, a receptacle within said compartment adapted to receive water to be frozen, a removable member within said compartment disposed below said receptacle, said

removable member being normally disposed in intimate thermal contact with a wall portion of said evaporator and cooled thereby to a temperature below freezing, said receptacle having a plurality of perforations in its bottom wall through which water received therein drips onto said member, and said perforations being so spaced apart as to cause the water dripping from said receptacle, upon freezing, to build up on said member in the form of a plurality of ice blocks.

2. A refrigerating apparatus comprising in combination, a cabinet provided with a food storage chamber having an evaporator of a refrigerating system therein, said evaporator being formed to provide walls of a freezing compartment within said chamber, a receptacle within said compartment adapted to receive water to be frozen, a removable member within said compartment disposed below said receptacle, said removable member being normally disposed in intimate thermal contact with a wall portion of said evaporator and cooled thereby to a temperature below freezing, said receptacle having a plurality of groups of perforations in its bottom wall through which water received therein drips onto said member, and the perforations of each of said groups thereof being so spaced apart as to cause the water dripping from said receptacle, upon freezing, to build up on said member in the form of a plurality of separated ice blocks.

3. A refrigerating apparatus comprising in combination, a cabinet provided with a food storage chamber having an evaporator of a refrigerating system therein, said evaporator being formed to provide a bottom wall and a plurality of other walls of a freezing compartment within said chamber, a non-metallic receptacle within said compartment disposed above the bottom wall thereof and adapted to receive water to be frozen, a removable metal tray within said compartment and supported upon the bottom wall of said evaporator whereby the tray is cooled to a temperature below freezing, said receptacle having a plurality of perforations in its bottom wall through which water received therein drips onto said tray, and said perforations being so spaced apart as to cause the water dripping from said receptacle, upon freezing, to build up on said metal tray in the form of a plurality of ice blocks.

4. A refrigerating apparatus comprising in combination, a cabinet provided with a food storage chamber having an evaporator of a refrigerating system therein, said evaporator being formed to provide a bottom wall and a plurality of other walls of a freezing compartment within said chamber, a non-metallic receptacle within said compartment disposed above the bottom wall thereof and adapted to receive water to be frozen, a removable metal tray within said compartment and supported upon the bottom wall of said evaporator whereby the tray is cooled to a temperature below freezing, said receptacle having a plurality of groups of perforations in its bottom wall through which water received there-

in drips onto said tray, and the perforations of each of said groups thereof being so spaced apart as to cause the water dripping from said receptacle, upon freezing, to build up on said metal tray in the form of a plurality of separated ice blocks.

5. A refrigerating apparatus comprising in combination, a cabinet provided with a food storage chamber having an evaporator of a refrigerating system therein, said evaporator being formed to provide a bottom wall and a plurality of upright walls of a freezing compartment within said chamber, a relatively long wide non-metallic receptacle supported within said compartment a substantial distance above the bottom wall thereof and adapted to receive water to be frozen, a relatively flat metal tray removably supported within said compartment upon the bottom wall of said evaporator whereby the tray is cooled to a temperature below freezing, said receptacle having a plurality of depressions in its bottom wall and each of the depressions being perforated to permit water received in said receptacle to drip onto said tray, and said perforated depressions being so spaced apart as to cause the water dripping from said receptacle, upon freezing, to build up on said tray in the form of a plurality of ice blocks.

6. The method of producing blocks of ice in a freezing compartment of a refrigerator cabinet which comprises, dripping water from a receptacle at spaced apart points upon a removable tray disposed in the freezing compartment and freezing the water to cause same to build up on the tray in the form of separated ice blocks.

7. The method of producing blocks of ice in a freezing compartment of a refrigerator cabinet which comprises, dripping water at spaced apart points from a receptacle in the freezing compartment to precool the water, and receiving the drops of precooled water on a tray in the freezing compartment to cause freezing and building up thereof on the tray in the form of separated ice blocks.

8. The method of producing blocks of ice in a compartment which comprises, dripping water from a source thereof at spaced apart points within the compartment upon a horizontally disposed surface and freezing the water to cause same to build up on the surface in the form of a plurality of ice blocks.

9. A refrigerating apparatus comprising in combination, a cabinet having a compartment therein, means associated with said compartment for receiving water, said means having perforations in a wall thereof to permit water to drip therefrom in said compartment, said apparatus including a surface beneath said means maintained below 32° F. and upon which the water drips, and said perforations being so spaced apart as to cause the water dripping from said means, upon freezing, to build up on said surface in the form of a plurality of ice blocks.
